UNITED STATES PATENT OFFICE.

JACOB BICKHART, OF HARLAN, INDIANA.

IMPROVEMENT IN PORTABLE FENCES.

Specification forming part of Letters Patent No. 35,581, dated June 17, 1862.

To all whom it may concern:

Be it known that I, JACOB BICKHART, of Harlan, in the county of Allan and State of Indiana, have invented a new and Improved Portable Fence; and I do hereby declare that the following is a full, clear, and exact description of the same, reference being had to the accompanying drawings, forming a part of this specification, in which—

Figure 1 represents a transverse vertical section of my invention. Fig. 2 is a face view of the same.

Similar letters of reference in both views indicate corresponding parts.

This invention consists in the arrangement of braces with V-shaped edges catching into corresponding notches in the edges of the posts near to their upper ends, in combination with a cross-brace, the ends of which form hooks and catch over the lower edges of said cross-braces and with a wedge and semicircular gib, in such a manner that by the action of cross-brace on the lower ends of the braces the upper ends of the posts are held together, and by the action of the semicircular gib and wedge, which forces the cross-brace down, the lower end of the posts are prevented spreading.

To enable those skilled in the art to make and use my invention, I will proceed to describe it with reference to the drawings.

The ends of panels A are confined between the upright posts B B', and these posts are held together and retained in an upright position by braces C C'. The edges of these braces are V shaped, and the upper edge of the brace C' catches into a corresponding V-shaped notch, a, in the upper part of the post B', and its lower edge into a similar notch, a, in the post B, and in a similar manner the upper edge of brace C is confined in a notch in post B and its lower edge in a notch in post B' on the opposite side of the brace C', as clearly shown in Fig. 1 of the drawings. The lower ends of braces C C' are forced toward each other by a cross-brace, D, which passes through a mortise in the lower ends of posts B B', and the ends of which form hooks c c', which catch over the edges of braces C C'.

It is obvious that by forcing the cross-brace D down the upper ends of the braces C C', and with them the upper ends of posts B B', are forced together, and the ends of the panels are firmly retained between said posts.

The cross-brace D is held down by a wedge, d, and gib e, and the gib is made semicircular, so that its ends catch over the edges of the mortise in the lower ends of posts, and prevent them spreading. By driving in the wedge d the gib e is forced up, and the lower ends of posts are firmly confined by its action on the edges of the mortise, and at the same time the cross-brace D is forced down, thereby closing up the braces C C', and with them the upper ends of posts. By means of wedge d, therefore, the posts are made to confine the ends of panels firmly and without the use of rails.

The upper ends of braces C C' may be confined in brackets E E', which are attached to the upper ends of posts, and which are provided with dovetailed grooves to receive the ends of braces. These brackets give an additional hold to the braces, and they add to the firmness of the upper ends of the posts; but they are not absolutely necessary to render the fence firm, and if it is desired to build a cheap fence they can be dispensed with.

This fence is exceedingly simple in its construction, and it can easily be taken apart or put up in any desired locality.

Having thus fully described my invention, what I claim as new, and desire to secure by Letters Patent, is—

The arrangement of the wedge d, gib e, and hooked cross-brace D, in combination with the braces C C' and notches a a' in the upper ends of posts B B', all constructed and operating substantially in the manner and for the purpose shown and described.

JACOB BICKHART.
